UNITED STATES PATENT OFFICE.

ALVIN L. JOHNSON, OF WORCESTER, MASSACHUSETTS, ASSIGNOR, BY MESNE ASSIGNMENTS, TO HI-LO JACK COMPANY, OF WORCESTER, MASSACHUSETTS, A CORPORATION OF MASSACHUSETTS.

JACK.

1,204,276.

Specification of Letters Patent.

Patented Nov. 7, 1916.

Application filed August 18, 1915. Serial No. 46,185.

To all whom it may concern:

Be it known that I, ALVIN L. JOHNSON, a citizen of the United States, residing at Worcester, in the county of Worcester and State of Massachusetts, have invented a new and useful Jack, of which the following is a specification.

This invention relates to a jack capable of general use but particularly adapted for use in connection with an automobile.

The principal objects of the invention are to provide a very simple well balanced jack having a relatively great leverage; which can be moved in under the machine in a convenient manner even when the wheels are down in a rut so that there is very little space between the ground and the axle; in which although a screw is used in operation, yet it is not necessary to move the mechanism along the screw by means of the ratchet handle when the device is not in actual operation; and which will be comparatively inexpensive, yet have few parts likely to get out of order in practice, and which can be folded into a very small compass and will be light in weight.

Reference is to be had to the accompanying drawings, in which—

Figure 1 is a side view of a jack constructed in accordance with this invention showing it substantially folded up; Fig. 2 is a plan of the same with parts in section; and Fig. 3 is a view similar to Fig. 1 showing the device in use.

The invention is shown in a form in which it involves a base 10 and rest 11 for receiving the axle or other part to be raised or lowered. These are connected by a parallel link construction comprising four links 12. Each of these links is provided with a segment 13 on one end, these segments being cast or punched out integral with the links. Each link is also pivoted at the other end to one of the other links. The two pivots thus provided are in the form of studs 14 and 15. On the studs are hubs 16 and 17. A screw 18 passes freely through these hubs. The two hubs therefore are in alignment and are both pivoted to the pivot members 14 and 15. The stud 14 extends through the screw 18, thus holding it at that end. On one of the studs 15 are fixed a bevel gear 19 and a ratchet wheel 20. A ratchet lever 21 having a double pawl 22 adapted to be held in either of its two positions by a spring 23

is pivoted on the stud 15. Engaging with the screw thread is a second bevel gear or pinion 24. This is adapted to mesh with the gear 19.

In operation it will be clear that the hub 17 can be moved along the screw until the rest 11 comes substantially into a position to engage the axle or other part to be raised or lowered. Then the gear 24 can be screwed up on the screw in a very expeditious manner until it engages the end of this hub and also meshes with the gear 19. The rest is then allowed to settle back until the gears come fully into mesh. Then, the pawl 22 having been placed in the right position, the handle 21 is oscillated and the two gears turned. This forces the hub 17 to travel along the screw thread with the gear 24 and the four links 12 are forced to turn positively with each other. The gear segments 75 keep the rest 11 in central position and no guide extending from the base 10 to the rest 11 is required. Likewise when it is desired to fold it up the rest is raised which moves the gear 24 out of contact with the gear 19 80 then the former is turned along the screw substantially to the end thereof. After that the rest 11 can be lowered to the position shown in Fig. 1 instantaneously.

It will be seen that the jack can be made 85 of light materials and is further lightened by the use of the gear segments instead of a guide for the rest and that it is light, compact, and easily and rapidly raised to its operative condition or folded up.

Although I have illustrated and described only a single embodiment of the invention I am aware of the fact that many modifications can be made therein by any person skilled in the art without departing from the 95 scope of the invention as expressed in the claims. Therefore, I do not wish to be limited to all the details of construction herein shown and described, but

What I do claim is:—

1. In a jack, the combination of a supporting base, a pair of links pivotally supported thereon, integral means on said links for causing them to partake of each other's movement and to rise or fall together about 105 their pivots, a second pair of links pivoted to the free ends of the first pair and pivotally connected at their other ends, a rest carried by the second pair of links, means integral with the second pair of links for 110

causing them to move simultaneously in opposite directions, and means for moving the pivotal connections between the two pairs of links toward or from each other 5 to raise or lower the rest.

2. In a jack, the combination of a supporting base, a pair of links pivotally supported thereon, a second pair of links pivoted to the free ends of the first

10 pair and pivotally connected at their other ends, a rest carried by the second pair of links, means integral with the second pair of links for causing them to move simultaneously in opposite directions, and means 15 for moving the pivotal connections between the two pairs of links toward or from each other to raise or lower the rest.

3. In a jack, the combination of a supporting base, two pairs of links pivoted 20 together to form a parallelogram, means integral with certain of said links for causing the two on one side to move with those on the other side of the base, but to move oppositely, a rest at the top connected with 25 the links, and means for directly forcing said links toward or from each other at the center to raise or lower the rest.

4. In a jack, the combination of a supporting base, two pairs of links pivoted together to form a parallelogram, means integral with certain of said links for causing the two on one side to move with those on the other side of the base, but to move oppositely, a rest at the top connected with 35 the links, a non-rotatable horizontal screw having a uniform thread from end to end, pivotally connected with the point at which the links on one side are pivoted together and slidably connected with the opposite 40 pivotal point, a nut fitting the screw-threads and entirely free from the slideable connection, and means for turning the nut.

5. In a jack, the combination of a base, a pair of links pivoted thereto, a second 45 pair of links each pivotally connected with

one of the other links and pivotally connected together, a work rest carried thereby opposite the base, a screw for forcing the connected ends of the two pairs of links toward or from each other, and means independent of said screw and located on the second pair of links for causing the links of the pairs to move simultaneously and equally.

6. In a jack, the combination of a base, 55 a pair of links pivotally mounted on said base and having integral gear segments thereon in the planes of the links meshing with each other whereby each link partakes of the motion of the other but in an opposite direction, and means at the top of said links for forcing the tops apart or together simultaneously.

7. In a jack, the combination of a base, 65 a pair of links pivotally mounted on said base and having integral gear segments thereon meshing with each other whereby each link partakes of the motion of the other but in an opposite direction, another pair of links pivoted to the top of the first 70 mentioned links, a rest above them to which the second pair of links are pivoted, said second links having gear segments integral therewith meshing with each other under said rest, and means at the points at which 75 the first pair of links are connected with the second pair for forcing the pivotal points away from or toward each other to lower and raise the rest.

8. In a jack, the combination of a supporting base, a pair of links pivotally supported thereon, means on said links for causing them to partake of each other's movement and to rise or fall together about their pivots, a rest supported by said links, 85 and means independent of the first named means for raising said links and rest.

In testimony whereof I have hereunto set my hand.

ALVIN L. JOHNSON.
